UNITED STATES PATENT OFFICE.

WALTER DORNHEIM, OF LEIPZIG, GERMANY.

STAMP-AFFIXING MACHINE.

1,113,420.

Specification of Letters Patent.

Patented Oct. 13, 1914.

Application filed September 28, 1912. Serial No. 722,925.

To all whom it may concern:

Be it known that I, WALTER DORNHEIM, a subject of the German Emperor, residing at Leipzig, in Germany, have invented a new and useful Stamp - Affixing Machine, of which the following is a specification.

This invention relates to a device for affixing stamps, labels and the like, to envelopes, cards, boxes, bottles and other packages.

10 An object of the invention is to provide a device by means of which stamps or similar objects may successively be attached to articles or packages of the described kind.

Another object of the invention is to provide a stamp receptacle from which stamps may be withdrawn successively by elements passing the receptacle in an intermittent uni-directional movement, said movement being imparted to the elements by a member 20 which alternately moves in opposite directions.

Another object of the invention is to provide means for removing the stamp withdrawn from said elements without interrupting their movement and to press the removed stamp by means of said members against the article to which the stamp is to be affixed.

Another object of the invention is to provide means for moistening the surface of the stamp withdrawing members without interrupting their movement.

Still another object of the invention resides in the arrangement of the stamp receptacle and the stamp withdrawing element movable relatively to each other so as to bring these parts at predetermined intervals into operative position.

With these and other objects in view I 40 have illustrated some embodiments of my invention in the accompanying drawing.

Figure 1 is a side elevation partly in section, of a device for affixing stamps; Fig. 2 is a top plan view; Fig. 3 is a side elevation 45 of certain parts of a modified device.

The frame *a*, has the shape of a box open at the top and at one end. The shaft, *b*, is rotatably supported in the lateral walls of the box, and projects beyond said walls. 50 Rigidly connected with the projecting ends of the shaft are two levers, *c*, which are connected at their front ends by the handle, *e*. A pressure plate *d*, extends between the two levers *c*, near their forward end and is secured to the outer sides of said levers by means of suitable fastening plates *2'* or the

like, and carries a layer of felt, *f*, or the like, at its under side. This plate is also provided with a locking means *g*, shown in the form of a lock in the drawing, and adapted to hold the lid *a'* of casing *a*, so as to prevent unauthorized operation of the device. Intermediate the lateral walls of the casing *a*, a toothed sector *h*, is rigidly connected with the shaft *b*, and is adapted to mesh with a gear, *i*, in the casing. The gear, *i*, is mounted on a shaft, *l*, which also carries a ratchet, *k*. Another gear, *m*, is loosely mounted on shaft *l*, adjacent the ratchet *k*, and which is in engagement with a pinion, *n*. The latter is rigidly connected with a roller, *o*, rotatably disposed in the interior of the casing. The gear, *m*, is also provided with a pawl, adapted to enter into operative engagement with the ratchet, *k*. The roller, *o*, is connected with the roller, *q*, near the bottom wall of the casing, by means of an endless belt, *p*. The belt is maintained under suitable tension by a roller, *r*, rotatably mounted in the walls of the casing. A box, *s*, having a lining or cushion of moisture-retaining material like sponge, felt, or the like, is adjustably disposed underneath the belt, *p*. In front of the roller, *q*, a wiping member, *t*, is held in stationary position and is adapted to scrape the belt when the latter is moved. Near the rear end of the box a receptacle *v* is mounted on an oscillatable bar *u*, said receptacle being connected with the bar so that it may readily be detached therefrom or replaced thereon.

An arm, *w*, rigidly connected with the rockshaft *w'* with which the bar *u* is connected, is under control of a cam *x*, rigidly mounted on the shaft *l*. A spring-controlled pin *y*, projects through the front wall of the casing into the path of the arm, *w*, as shown in Fig. 2. The position of this pin is indicated by a dotted circle in Fig. 1.

The entire device may be adjusted longitudinally with respect to an upright, *z*, disposed at the rear end of the device.

The rear wall of the box carries a bracket *z'* having four rollers *r'*, in engagement with the opposite surface of the upright. 105 The latter may be rigidly or removably disposed on the surface of a table or such like.

The modification shown in Fig. 3 illustrates a stationary receptacle *v*, for the stamps and a roller *o'*, which may be reciprocated in vertical direction with respect to said receptacle. For the purpose of im-

parting this movement to the roller an arm, 1, is rigidly mounted on shaft *b* near the inner surface of a lateral wall of the casing. A rod 2, projects into the path of said 5 arm and is maintained in proper position by link 3, which is under control of the spring 4; the spring serves for normally maintaining the roller *o* in its lowermost position.

10 The operation of the device is as follows: The casing *a* is adjusted to the proper height with respect to the surface *A*, and is held in said position by tightening the clamping screw *S'* on bracket *z'*, thus 15 tightening the plates of said bracket *z'* and locking the rollers *r'* tightly against rotation at the proper time whereupon they act by friction to hold the bracket in position on the upright, while the shank *s''* of 20 said clamping screw which is adapted to slide within and extending through a groove *z''* of the upright *z* is secured in its adjusted position on said upright by a nut *s'''* provided at the outer rear end of said 25 shank *s''*. This height above surface *A* should correspond with the approximate thickness of the articles to be labeled; the levers *c* should be nearly horizontal when the plate *d* rests upon the article to be 30 labeled. The receptacle *v* is detached from the transverse support *u*, and is filled with stamps, labels, or such like. The lining or cushion in the box, *s*, is thoroughly moistened. When the levers *c*, are swung 35 downwardly, the shaft *b* is rocked and the segment *h* is rotated through a predetermined arc. The ratchet *k* is thereby rotated and imparts rotation to the gear *m* loosely mounted on shaft *l*. The rotation 40 of the gear *m* is transmitted to the pinion *n*, which is rigidly connected with the roller, *o*, and which, therefore, is also rotated. The belt *p* moves in the direction indicated by the arrow. In passing over box *s*, this belt 45 takes some moisture from the cushion in the box as it is in sliding engagement therewith. The cam *x* on shaft *l* holds the arm *w* in raised position at the beginning of this movement. The transverse bar *w* 50 is swung backwardly and the receptacle *v* detachably connected therewith, is therefore in raised position. Near the end of the movement the arm *w* descends in accordance with the movement and shape of the 55 cam *x*, and the receptacle, *w*, is brought into operative position with respect to the face of the belt *p*. The labels or stamps are placed in the receptacle with their gummed side downwardly, and the lowermost 60 label or stamp will therefore stick to the moistened surface portion of the belt. When the levers *c* are again oscillated to the rockshaft *b*, the stamp on the belt is gradually conveyed downwardly, passing 65 underneath the roller, *r*. In the continued

movement of the belt the stamp is removed therefrom by means of the stationary wiper *t*. The article which is to be provided with the stamp has previously been placed in proper position, and the stamp scraped off the belt by wiper *t* will then be pasted upon this article by the felt of the plate *d*. When the levers *c*, are swung upwardly, the belt, *p*, is not moved because the teeth of the ratchet slide over the pawl *k* without actuating the same. 75

In the embodiment illustrated in Fig. 3, the arm 1 during the last part of the downward movement of the levers *c* rocks the rod 2 upwardly which displaces the roller 80 *o'* and brings the belt *p* in contact with the lowermost stamp within the receptacle *v*. During the upward movement of the levers *c*, the arm 1 is retracted and the spring 4 pulls the rod 2 and therefore also the roller 85 *o'* into the position in which these parts are shown in the drawing. 95

I claim:

1. A machine of the character described, comprising in combination a stamp receptacle, an endless stamp-conveying means, an oscillating shaft, elements connecting said conveying means with the oscillating shaft and serving to move said conveying means intermittently in one direction, means for 90 bringing said conveying means into engagement with the lowermost stamp in the receptacle, stationary means for removing the stamp from said conveying means, and an element for pressing the removed stamp 95 against the article to which it is to be attached. 100

2. A machine of the character described, comprising in combination a stamp receptacle, an endless stamp-conveying means, 105 elements for imparting uni-directional movement to said conveying means, elements for raising and lowering the stamp receptacle so as to bring the same intermittently into engagement with the stamp-conveying 110 means, stationary means for removing the stamp from said conveying means, and a manually operable element for pressing the removed stamp against an article and operatively connected to actuate said elements. 115

3. A machine of the character described, comprising in combination a stamp receptacle, an endless stamp-conveying means, elements for imparting uni-directional movement to said means, and for bringing 120 said receptacle and said stamp-conveying means into intermittent engagement, adjustable means for moistening the surface of said conveying means, both of said last-named means being in permanent frictional 125 engagement, stationary means for removing the stamp from said conveying means, and an element for pressing the removed stamp against the article to which it is to be attached. 130

4. A machine of the character described, comprising in combination a casing, a stamp receptacle mounted in said casing, an endless stamp-conveying means, elements for imparting uni-directional movement to said conveying means, and for bringing the same into intermittent engagement with the contents of said stamp receptacle, means stationary with respect to the casing for 5 moving the stamp from said conveying means, and an element movable with respect to the casing, for pressing the removed stamp against the article to which it is to be attached, a support for said casing and 10 means for adjusting said casing with respect to said support so as to bring the pressure means in horizontal position when said means are in operative position.

5. A machine of the character described, 20 comprising in combination a casing, a rock-shaft mounted in said casing, actuating levers for said shaft, a bridge-plate connect-

ing said levers, a toothed sector mounted on said rock-shaft, stamp-conveying means and transmission elements interposed between said sector and said conveying means for imparting uni-directional movement to said conveying means when the rockshaft is oscillated alternately in opposite directions; a stamp receptacle and means for intermittently moving the stamp receptacle so as to bring the contents thereof into engagement with the conveying means; a wiper fixed to the casing, said bridge-plate being adapted to press the stamp removed from the conveying means by the wiper against the article to which the stamp is to be attached.

In testimony whereof I affix my signature in presence of two witnesses.

WALTER DORNHEIM.
